UNITED STATES PATENT OFFICE.

GEORGE HENRY WHEARY, OF RACINE, WISCONSIN.

WARDROBE-TRUNK.

1,158,411.

Specification of Letters Patent.

Patented Oct. 26, 1915.

Application filed October 27, 1913. Serial No. 797,504.

To all whom it may concern:

Be it known that I, GEORGE H. WHEARY, a citizen of the United States, and resident of Racine, in the county of Racine and State of Wisconsin, have invented new and useful Improvements in Wardrobe-Trunks, of which the following is a description, reference being had to the accompanying drawings, which are a part of this specification.

10 This invention relates to improvements in wardrobe trunks of that type in which the clothes hangers are supported on extensible tracks mounted in the wardrobe section of the trunk and just beneath the door or cover 15 of the end portion of the trunk.

It is one of the objects of the present invention to provide a wardrobe trunk of the character described with hanger tracks which may be independently extended or 20 closed and are provided with means for clampingly locking the end cover in closed position.

25 A further object of the present invention is to provide a wardrobe trunk having a retainer bar mounted on both tracks which may be easily disengaged from both tracks or from one of the tracks and swung to a depending position to permit convenient access to the hangers mounted on the tracks.

30 A further object of the invention is to provide a wardrobe trunk with means for automatically locking the extensible bars in extended positions.

35 A further object of the present invention is to provide a wardrobe trunk having a removable retainer bar adapted to yieldingly engage teeth provided on the rails for locking the bar in different positions of adjustment.

40 A further object of the invention is to provide a wardrobe trunk of the character described which is of simple construction, is strong and durable and is well adapted for the purpose described.

45 With the above and other objects in view, the invention consists of the improved wardrobe trunk and its parts and combinations as set forth in the claims, and all equivalents thereof.

50 In the accompanying drawing in which the same reference characters indicate the same parts in all of the views: Figure 1 is a top view of a wardrobe trunk of the improved type, the top or cover and the rails being shown in open position and the drawer section being also indicated in open position

by dotted lines; Fig. 2 is a vertical sectional view taken on line 2-2 of Fig. 1; Fig. 3 is a similar view with the parts in closed positions; Fig. 4 is a detail view on a larger scale of an end portion of the retainer bar, and a cross sectional view of the track; and Fig. 5 is a detail view of one of the braces.

Referring to the drawing the numeral 8 indicates the wardrobe section of the improved wardrobe trunk, 9 the top cover and 10 the side cover or drawer section thereof. The top cover 9 is hinged to the upper rear end of the wardrobe section and at its front edge portion is provided with a reinforcing angular metal strip 11 having recesses 12 formed on its upper edge which are adapted to be engaged by hook members 13 for clampingly locking the cover in closed position. The hooks are pivotally connected 75 to supporting members 14 which are in turn pivoted at their inner ends to the outer ends of a U-shaped reinforcing strap 15, and this reinforcing strap is mounted within the wardrobe section near the upper end and 80 engages three side walls thereof.

Fixed tracks 16 mounted within the wardrobe section on opposite sides thereof and having their inner ends riveted to the rear portion of the U-shaped strap 15 are supported at their forward ends by curved brackets 17 which are mounted on the trunk sides and project downwardly and upwardly in a curve and engage the tracks medially between their side portions. Extensible tracks 18 having hinged connections 19 with the outer ends of the fixed tracks are rigidly connected at their outer ends to the curved outer ends 20 of the supporting members 14. The hinged connections 19 are in axial alignment with the pivotal connections of the supporting members 14 with the U-shaped strap 15, to permit the extensible tracks to be swung upwardly into horizontal alignment with the fixed tracks.

To provide a secure connection between the outer ends of the fixed tracks and the supporting members, the track ends are provided with slots 21 into which the ends of the supporting member extend and are riveted to the said track ends. The supporting members and the tracks connected thereto are held in horizontal positions by braces 22 which are pivoted at their upper ends to the supporting members, and their lower portions slide through and engage the lower portions of the brackets 17. The

lower ends of the braces are serrated or provided with teeth 24 which engage the loops of the brackets when the members have been swung upwardly and lock the extensible tracks in horizontal alignment with the fixed tracks so that it is only necessary to swing the supporting arms upwardly and the braces will automatically drop into locked positions. The teeth of the braces provided for compensating for the wear of the parts and to always hold the tracks rigid when extended.

The tracks are cylindrical in cross section and the inner portions of the fixed rails are cut transversely, vertically, to form saw teeth 25 which are engaged by the locking bolts 26 mounted on the retainer bar 27. The outer end portions of the bar are provided with circular openings 28 (only one being shown) and slots 29 communicating therewith which are of a width to permit the bar to be disengaged from the tracks when it is slid to its outer position and resting on the curved end portions of the supporting members. When in this position one end may be disengaged from one of the tracks to permit the bar to drop downwardly as indicated by dotted lines in Fig. 4. This position permits free access to garments supported on hangers 30 (only one being shown) without having detached parts lying around. While the extensible tracks are shown as rigidly connected to the supporting members as a preferred form, each track and member may be formed of one piece of material bent into U-shape similar to the form shown in the drawings without departing from the spirit and scope of the invention.

40 The locking bolts 26 of the retainer bar are held yieldingly in engagement with the teeth of the tracks by a coiled spring 31 which is interposed between the inner bent ends 32 of the bolts. The spring is held in position by a band 33 extending around the spring and fastened to the bar. The band also serves as a stop to limit the inward movement of the bolts. The teeth of the tracks incline inwardly so that the bar may be merely pushed inwardly and will snap over the teeth but will be held against outward movement until the bolts are withdrawn. The upper door or cover 9 is held in open position by the slotted brace member 33 of ordinary construction.

From the foregoing description it will be seen that the tracks may be extended in a very simple manner and that when it is desired to lock the top cover in closed position each side portion may be independently engaged by its respective hook and firmly clamped and locked in position by swinging the extensible track and the supporting member to which the hook is attached downwardly. The construction also permits the

retainer bar to be easily moved inwardly or outwardly or entirely detached from the tracks or detached from one track and swung downwardly out of the way on the other track.

What I claim as my invention is:

1. A trunk comprising a compartment provided with a hinged cover, and independently movable arms pivoted to the compartment walls to swing downwardly and provided with hook members adapted to engage different portions of the hinged cover and clampingly and independently draw the engaged portions to closed positions.

2. A trunk, comprising a compartment provided with a hinged cover, extensible hanger tracks independently mounted within the compartment, independent supporting members pivoted to the compartment walls and connected to the extensible portions of the tracks and movable therewith, hooks pivoted to the supporting members and adapted to engage different portions of the cover and clampingly and independently draw the engaged portions to closed positions, and means for holding the supporting members in one of their positions of adjustment.

3. A trunk, comprising a compartment provided with a hinged cover, fixed tracks mounted within and on opposite sides of the compartment, extensible tracks hinged to the outer ends of the fixed tracks and adapted to swing upwardly into horizontal alignment with the fixed tracks, independently movable supporting members connected at their outer ends to the free ends of the extensible tracks and having their inner ends pivoted to the walls of the compartment, hooks pivoted to the supporting members for engaging portions of the cover to clampingly and independently draw the engaged portions to closed positions, and brace members for independently holding the supporting members in their upper positions.

4. A trunk, comprising a compartment provided with a hinged cover, fixed tracks mounted within and on opposite sides of the compartment, extensible tracks hinged to the outer ends of the fixed tracks and adapted to swing upwardly into horizontal alignment therewith, supporting members pivoted to the opposite sides of the compartment and having their outer end portions connected to the outer ends of the extensible tracks and projecting outwardly beyond said track ends, the outer portions of the supporting members being of less thickness horizontally than the tracks, means for holding the supporting members in their upper positions, and a retainer bar slidably mounted on the tracks and removable therefrom only when in its outer position and above the outer portions of the support.

5. A trunk, comprising a compartment provided with a hinged door, extensible tracks mounted within and on opposite sides of the compartment, supporting members connected to the outer ends of the tracks and pivotally connected to the compartment walls, the outer end portions of the supporting members being of less thickness than the tracks, a retainer bar provided with openings through which the tracks extend and with communicating slots to permit the bar to be removed from and mounted on the tracks at the junction of the supporting members with the tracks, means for locking the retainer bar in different positions of adjustment on the tracks, and means for holding the extensible portions of the tracks in positions of adjustment.

6. A trunk, comprising a compartment provided with a hinged door, toothed extensible tracks mounted within and on opposite sides of the compartment, supporting members connected to the outer ends of the tracks and pivotally connected to the compartment walls, the outer end portions of the supporting members being of less thickness than the tracks, a retainer bar provided with openings through which the tracks extend and with communicating slots to permit the bar to be removed from and mounted on the tracks at the junction of the supporting members with the tracks, spring actuated bolts mounted on the retainer bar for engaging the teeth to lock the bar in different positions of adjustment on the tracks, and means for holding the extensible portions of the tracks in positions of adjustment.

7. A trunk, comprising a compartment having a hinged cover, fixed rails mounted within the compartment, independent extensible rail members hinged to aline with the fixed rails and to swing downwardly, and means carried by each extensible rail for engaging a portion of the cover and clamping it and independently drawing it to closed position.

8. A trunk, comprising a compartment having a hinged cover, fixed rails mounted within the compartment, brackets supporting the outer end portions of said rails, independently movable extensible rail members hinged to aline with the fixed rails, and independent means engaging the bracket for holding the extensible rails in positions of adjustment.

9. A garment hanger support for a trunk, comprising a pair of spaced tracks mounted within the trunk, U-shaped members pivotally connected to the outer ends of the tracks and to the trunk sides and adapted to be independently swung downwardly to closed positions, the stems of the U-shaped members which are connected to the tracks serving as extensible rails, and means for

holding the U-shaped members in open positions.

10. A garment hanger support for a trunk, comprising a pair of spaced tracks mounted within the trunk, U-shaped members pivotally connected to the outer ends of the tracks and to the trunk sides and adapted to be independently swung downwardly to closed positions, the stems of the U-shaped members which are connected to the tracks serving as extensible rails, and brace members pivotally connected to the U-shaped members and engaging portions of the trunk for holding the U-shaped members in open position.

11. A garment hanger support for a trunk, comprising a pair of spaced tracks connected at their rear ends to the trunk, brackets connecting the forward ends of the rails to the trunk, U-shaped members pivotally connected to the outer ends of the tracks and to the trunk sides and adapted to be independently swung downwardly to closed positions, the stems of the U-shaped members which are connected to the tracks serving as extensible rails, and brace members pivotally connected to the U-shaped members and engaging the brackets for holding the U-shaped members in open positions.

12. A garment supporting fixture, comprising a supporting frame having an open side, a pair of hanger supporting members spaced apart and away from the sides of said frame, each hanger supporting member consisting of a stationary rod fixedly secured to said frame, and an independently movable rod pivoted to each stationary rod and adapted to be independently moved into alinement therewith and also at an angle thereto, brackets secured to the frame and supporting the forward ends of the stationary rods, and brace members, one for each movable rod and pivoted thereto, said brace members being adapted to bear against said brackets whenever the movable rods are in alinement with the stationary rods, but operable independently of each other.

13. A garment hanger support for a trunk, comprising a U-shaped metal band constructed to be connected to a trunk, U-shaped brackets secured to the side arms of said band and extending toward each other, fixed tracks connected to the rear portion of the band and to the inner parts of the U-shaped brackets, extensible tracks hinged to the outer ends of the fixed tracks and adapted to be independently swung to open positions in longitudinal alinement with the fixed tracks to which they are respectively hinged, and brace arms carried by the extensible tracks and engaging the U-shaped brackets for holding said extensible rails in open position.

14. A garment hanger support for a

- trunk, comprising fixed tracks adapted to be connected at their rear ends to the rear portion of a trunk, side members for connecting the forward end portions of the fixed tracks to the side portions of the trunk, extensible tracks hinged to be independently swung to open positions in longitudinal alignment with their respective fixed tracks, and brace members positioned to engage the side members and the extensible tracks and to hold said extensible tracks in aligned positions with their fixed tracks.
15. A garment supporting fixture, comprising a supporting frame, having an open side, a pair of hanger supporting members, spaced apart and away from the sides of said frame, each hanger supporting member comprising a stationary rod fixedly secured to said frame, and a movable rod pivoted to the stationary rod and adapted to be moved into alignment therewith and also at an angle thereto, brackets secured to the frame and supporting the forward ends of the stationary rods, and brace members, one for 20 each movable rod and pivoted thereto, said

brace members being adapted to bear against said brackets whenever the movable rods are in alignment with the stationary rods, but operable independently of each other.

16. In a garment supporting fixture, a 30 supporting member, a pair of spaced, hanger supporting members, each comprising a hanger supporting rod fixedly mounted at both ends on said supporting member, and a movable hanger supporting rod pivotally 35 secured to said fixedly supported rod at its forward end, and capable of being swung into alignment therewith independently of the other movable rod, and brace members, one between each movable rod and the supporting member, said brace members being pivoted directly on said movable hanger supporting rods.

In testimony whereof, I affix my signature, in presence of two witnesses.

GEORGE HENRY WHEARY.
